NURSING BOTTLE CLOSURE SHIELD

Paul Meeker, 412 Park, Kent, Ohio 44240

Filed May 8, 1974, Ser. No. 468,155

Term of patent 14 years

Int. Cl. D7—01

U.S. Cl. D83—8 A

—FIG.3

FIG. 1 is a side elevation of a nursing bottle closure shield showing my new design;

FIG. 2 is a top plan view thereof; and

FIG. 3 is a bottom plan view thereof.

I claim:

The ornamental design for a nursing bottle closure shield, as shown.
